Attorneys

UNITED STATES PATENT OFFICE.

ROBERT V. DAY, OF DOUGLAS, GEORGIA.

TRUCK BODY.

Application filed March 13, 1922. Serial No. 543,254.

To all whom it may concern:

Be it known that I, ROBERT V. DAY, a citizen of the United States, residing in Douglas, county of Coffee, and State of Georgia, have invented certain new and useful Improvements in Truck Bodies; and I do hereby declare the following to be a full, clear, and exact description of the invention, such as will enable others skilled in the art 10 to which it appertains to make and use the same.

The present invention relates to improvements in truck bodies, and more particularly relates to an improved body for the holding 15 of bottled goods in cases in such manner that they will not be apt to slide out of the shelving provided in the body for the same especially when the vehicle is rounding corners at relatively great speed.

It is an object of the invention to provide a truck body in which the shelving extends at an inclination downwardly and toward the longitudinal center of the body in such wise that the case goods will be supported 25 at a downward inclination and will have to ride upwardly in order to escape from the shelves.

A further object of the invention resides in providing an improved truck body of a simple and inexpensive construction in combination with a novel form of shelving and brace work, in connection with a sign board extending longitudinally across the top of the truck body.

With the foregoing and other objects in view, the invention will be more fully described hereinafter, and will be more particularly pointed out in the claim appended hereto.

In the drawings, wherein like symbols refer to like or corresponding parts throughout the several views,

Fig. 1 is a side elevational view of an improved truck body constructed according to the present invention;

Fig. 2 is an end view thereof; and

Fig. 3 is a fragmentary perspective view showing a portion thereof.

Referring more particularly to the drawings, 1 designates the bed or foundation of the truck body which is placed upon the running gear in the usual manner, and 2 and 3 are side boards erected upon the bed or foundation, which, in combination with 55 the end boards 4, form an enclosed base.

Standards 5 are erected at the corners of

the base and intermediate standards 6 midway the length of the truck body, such standards being preferably of angle iron construction, as more particularly seen in Fig. 60 3, and being held on the ends of angle rails 7 lying within the end boards 4. Central standards are also erected upon the base or foundation and they preferably consist of flat band metal returned upon itself to provide a pair of legs 8 and 9 extending upwardly in convergent relation to the level of the top shelving where the leg 9 is discontinued, the leg 8 being continued upwardly to form a central brace member 10 70 lying above the longitudinal center of the truck body.

At the divergent lower ends of the legs 8 and 9 a strap 11 is formed in one piece with the metal and lying flat against the 75 end rail 7, as shown in Fig. 3, and being secured thereto as by rivets or other fastenings 12. The legs 8 and 9 form appropriate supports for the flanged rails 13 and 14 which extend longitudinally of the truck 80 body and are mounted in pairs and in superposed rows. These flanged rails 13 and 14 cooperate with other flanged rails 15 and 16 secured to the uprights 5 and 6, as also shown in Fig. 3. 85

The rails 15 and 16 are respectively at higher elevations than the rails 13 and 14, and they are adapted to receive slats 17 which incline downwardly towards the central part of the truck body, thus affording 90 shelving of a character to effectively hold the cases of bottled goods in place. The shelving is of course open at its sides in order to permit of the insertion and removal of the cases. The lowermost intermediate 95 angle irons are supported upon the end rails 7, as shown in Fig. 3, and suitable tie bars 18 are mounted across the ends of the standards and uprights and are secured thereto as by rivets or other fastenings, the 100 tie bars 18 being preferably bent to lie substantially parallel with the shelves and at a slight elevation thereabove to catch the sides of the cases whereby to avoid their escape through the ends of the body. 105

The end uprights 5 are continued upwardly and bent to form diagonal braces 19 and 20 converging centrally and meeting with the top edges of the central braces 10 to which they are appropriately secured. 110 A sign board 21 is secured in any desired manner to the braces 10 or to other parts,

and may desirably bear the name of the manufacturer or advertising matter in connection with the goods transported.

In use, the body so built up will be mounted upon a truck and the case goods will be placed through the open sides of the shelving and will be allowed to descend into contact with the angle bars 13 and 14 which are spaced suitably apart by the divergent character of the legs 8 and 9 so as to prevent the cases from coming together. The cases will thus be supported upon the slats 17 and they will have a tendency to ride down toward the middle of the body and will not be apt to be thrown outwardly by centrifugal force when the truck is rounding a corner. The escape of the case will also be prevented by the angle flanges of the bars 15 and 16.

20 It will be appreciated from the foregoing that I have provided a simply constructed truck body for the handling and transportation of case goods which will effectively hold the cases against any tendency to escape laterally from the shelving of the body, and which will further permit of the easy introduction of the cases into the shelving and their ready and easy removal there-

from. The construction as a whole forms a strong unit being braced in the several directions in which strain is apt to occur and being of an inexpensive character.

It is obvious that various changes and modifications may be made in the details of construction and design of the above specifically described embodiment of this invention without departing from the spirit thereof, such changes and modifications being restricted only by the scope of the following claim.

40 What is claimed is:—

An improved truck body comprising a bed, uprights extending from the bed at the outer edges of the body, supporting standards placed along the median line of the body, rails carried by said uprights and standards, the rails carried by the standards being lower than the rails carried by the uprights, slats removably carried by the rails and inclining downwardly toward the center of the truck body, braces at the upper portion of the standards and uprights, and a sign board carried by said braces, substantially as described.

45 50 ROBERT V. DAY.
